[57] CLAIM

The ornamental design for a vehicle camper shell, as shown and described.

DESCRIPTION

FIG. 1 is a rear side perspective view of a vehicle camper shell showing my design;

FIG. 2 is a top plan view thereof;

FIG. 3 is a front elevational view thereof;

FIG. 4 is a right side elevational view thereof;

FIG. 5 is a rear elevational view thereof;

FIG. 6 is a bottom plan view thereof;

FIG. 7 is a rear side perspective view of a vehicle camper shell showing a second embodiment of my new design, the sole difference being in the omission of the side windows;

FIG. 8 is a rear side perspective view of a vehicle camper shell showing a third embodiment of my new design, the sole difference being in the appearance and shape of the side windows;

FIG. 9 is a rear side perspective view of a vehicle camper shell showing a fourth embodiment of my new design, the sole difference being in the appearance and shape of the side windows; and

FIG. 10 is a rear side perspective view of a vehicle camper shell showing a fifth embodiment of my new design, the sole difference being in the appearance and shape of the side windows.

FIG. 1

FIG. 2

FIG. 3
